HYDRAULIC POWER ACTUATOR

Theo Sherwen, Norton Lindsey, England, assignor
to Harry Ferguson, Limited, Coventry, England,
a British company

Application November 8, 1951, Serial No. 255,512

1 Claim. (Cl. 121—38)

1 The present invention relates generally to hydraulic ram or actuator devices and, more specifically, to hydraulic actuators which are particularly well adapted for operating agricultural implements from tractors having hydraulic power systems.

One object of the invention is to provide an actuator of the type set forth and which is of simple, inexpensive construction, most of its parts being susceptible of fabrication from materials requiring little, if any, machining.

Another object is to provide an actuator of the foregoing character and which possesses ample ruggedness and reliability in operation to adapt it for the rigorous usage occurring in agricultural applications.

Other objects and advantages will become apparent as the following description proceeds, taken in connection with the accompanying drawing, in which:

Figure 1 is a sectional view through an illustrative actuator embodying the present invention, such view being taken on the longitudinal axis of the actuator.

Fig. 2 is an enlarged transverse sectional view through the actuator of Fig. 1 and in the plane of the line 2—2.

Fig. 3 is an enlarged, fragmentary detailed sectional view of the gland assembly of the actuator shown in Fig. 1.

Fig. 4 is an enlarged fragmentary sectional view showing a slight modification in the closed end of the actuator cylinder.

While the invention is susceptible of various modifications and alternative constructions, a preferred embodiment has been shown in the drawing, and will be described below in considerable detail. It should be understood, however, that there is no intention to limit the invention to the specific form disclosed, but on the contrary, the intention is to cover all modifications and alternative constructions falling within the spirit and scope of the invention as expressed in the appended claim.

Upon more specific reference to the drawing, it will be perceived that the invention is there exemplified in illustrative hydraulic actuator 10. The same comprises a tube or cylinder 11 which telescopically houses a slideable plunger 12 of sub-

stantially smaller diameter than that of the cylinder bore. In the present instance, the plunger 12 happens to be of tubular form for the purpose of conserving weight and material. It may, however, be made in the form of a solid rod, particularly in the case of an actuator of relatively small diameter. One end of the cylinder 11 (the left hand end as shown in Fig. 1) has a closure member in the form of a flanged plug 14 secured thereto as by means of an annular weld 15. Fixed to, or integral with the plug 14, is an attaching eye 16 which may be pivotally secured to a reaction point or anchorage. The outer or projecting end of the plunger 12 is provided with a plug 18, secured thereto as by means of an annular weld 19, the plug having an eye 20 adapted for pivotal connection with the mechanism to be actuated. Pressure fluid may readily be admitted to or exhausted from the cylinder 11 via an opening 21 in its side wall and an appropriate conduit connection 22 fastened to the cylinder in registry with the opening 21. The end of the cylinder 11 remote from the plug 14 houses a gland assembly 23 serving as a seal for the slideable plunger 12.

For the purpose of guiding the head or left-hand end of the plunger 12 axially of the bore in the cylinder 11, the plunger is provided with a guide collar 24 (Fig. 1). This collar is defined by two arcuate or segmental bearing shoes 25, 26 which may be of sintered metallic or of die-cast construction. The arcuate bearing shoes 25, 26 are mounted within an annular groove 27 in a spool-shaped member 28 defining the inner end of the plunger 12. The spool-shaped member has an extension 29 which fits inside and closes the tubular body of the plunger 12, being attached to the same by means of an annular weld 30. The arcuate shoes 25, 26 have slight clearances "C" and "D" relative to the medial portion of the spool-shaped member 28 and the inner periphery of the cylinder 11, respectively (see Fig. 2). The shoes 25, 26 also have a more substantial clearance relative to each other, defining gaps 31 between their adjacent ends. The foregoing arrangement renders the members 25, 26 and hence the guide collar 24, susceptible of a slight floating movement in a plane transverse to the longitudinal axis of the cylinder 11 and the stroke of the plunger 12. This enables the collar 24 to com-

pensate for slight longitudinal or circumferential irregularities which might exist within the bore of the cylinder 11 in event the latter is made of seamless drawn tubing without being machined or honed.

In order to receive the gland assembly 23, the right hand end of the cylinder 11 (as viewed in Fig. 1) has a counterbore 32 with a narrow annular groove 34 adjacent its outer end. The gland assembly 23 is simply telescoped into the counterbore 32 and retained in place by means of a split spring ring 34A which snaps into the groove 34.

The gland assembly 23 comprises inner and outer cupped rings 35, 36, of sintered bronze or similar bearing material, through which the plunger 12 slidably passes. The cupped ends of the rings 35, 36 face each other and grip between them a reinforced sealing ring 38 of rubber or similar resilient material, these parts being preferably dimensioned so that the ring 38 will be compressed to a certain extent when initially installed. The sealing ring 38 has bonded thereto a reinforcing ring 39, preferably of steel. The reinforcing ring 39 has a stepped-up portion disposed so that it makes metal to metal contact with the adjacent face of the outer cupped ring 36. The inner cupped ring 35, however, contacts only the resilient material of the sealing ring 38, the adjacent outer contacting edge of the ring 35 being formed with a chamfer 43 to facilitate squeezing of the resilient material of the ring 38 out against the counterbore 32 and increase the sealing area.

Provision is made for effecting a further increase in the sealing action of the ring 36 as the plunger 12 reaches the outer end of its stroke. This is accomplished by the simple expedient of applying a thrust from the plunger against the gland assembly 23, thereby forcing the inner cupped ring 35 closer toward the outer ring 36 and effecting a supplemental squeeze on the sealing ring 38. In other words, the compressive force on the ring 38 due to its initial compression and also due to the action of pressure fluid on the exposed annular area of the cupped ring 35 has superimposed thereon an additional compressive force due to the action of pressure fluid against the inner end face of the plunger 12. In the present instance, a stop sleeve 41 is interposed between the inner cupped ring 35 and the guide collar 24 on the plunger 12. The sleeve 41, the length of which defines the outer extremity of the plunger stroke, is of somewhat larger diameter than the body of the plunger 12 and may be fastened to the inner cupped member 35 or, alternatively, may simply be disposed in free floating relation on the body of the plunger 12.

In operation of the actuator 10, it will be appreciated that as the plunger 12 approaches the outermost extremity of its stroke, the arcuate bearing shoes 25, 26 of the guide collar 24 will be accosted by the inner end of the stop sleeve 41. At this point, the inner cupped ring 35 will be subjected to an outward compression force resulting from the application of pressure fluid over a total area equivalent to the full cross-sectional area of the bore of the cylinder 11. Under these conditions, the inner portion of the resilient sealing ring 38 is flared or swelled out inside the recess defined within the cupped rings 35, 36 to provide a relatively large sealing face 42 bearing against the plunger 12. To facilitate effective contact between the face 42 and the

plunger 12, the former may initially have a slight concave contour.

With the actuator 10 in the condition shown in Fig. 1 and the plunger 12 at the inner extremity of its stroke, the pressure fluid acting on the spool member 28 will normally create a sufficient outward thrust to start the plunger 12 in motion. In actual practice this initial starting thrust would probably be enhanced due to the fact that a certain amount of inherent roughness on the contacting faces of the plug 14 and the spool member 28 would permit pressure fluid to enter between them and create an additional starting thrust. In some instances, however, it might be desirable to make more positive provision for the application of a consistently high starting thrust to the plunger 12. Referring to Fig. 4, there may be interposed between the adjacent faces of the plug 14 and the spool-shaped member 28 a suitable stop abutment or spacer 44 capable of maintaining a definite and predetermined space 45 between these members so that pressure fluid may immediately exert a substantial thrust upon the inner end of the plunger. The abutment 44 may be of relatively small size and may be attached either to the plug 14 or to the spool-shaped member 28 of the plunger.

The construction described herein embodies a number of features, all contributing to the production of an inexpensive hydraulic actuator which may be applied, for example, to agricultural implements associated with tractors having hydraulic power systems to perform movements hitherto requiring manual operation and without making the cost prohibitive. In the event that the cylinder 11 should be made from cold drawn seamless tubing, its inner bore need not be machined or honed because it is only called upon to form a guide and not a sealing surface for the arcuate shoes of the guide collar 24. Since the latter are susceptible of slight floating movement, they may readily adapt themselves to small irregularities in the inner surface of the cylinder 11, either in the axial or circumferential direction. The clearances which make such floating movement possible, as well as the gaps 31 between the ends of the members 25, 26, also permit oil to flow readily past them during operation of the actuator. In addition, the readily insertable and easily secured gland assembly 23 obviates the use of a screwed gland and the necessity for forming relatively large diameter screw threads inside the bore of the cylinder 11.

I claim as my invention:

In a hydraulic actuator, the combination comprising a tubular cylinder having a counterbore adjacent one end thereof, a flanged plug closure member rigidly fixed to the opposite end of said cylinder, said plug having an anchoring connection thereon, means for admitting pressure fluid into said cylinder or exhausting it from the same, a plunger slidably housed within said cylinder and terminating at its inner end in a spool shaped member, the opposite end of said plunger terminating in a fixed plug having connecting means thereon, a pair of arcuate guide shoes mounted on the medial portion of said spool shaped member with their adjacent ends in spaced apart relation, said arcuate shoes being susceptible of limited floating movement in a direction transverse to the plunger stroke, a pair of cup-shaped ring members mounted within said

counterbore in straddling relation with a resilient sealing ring, means adjacent the outer end of said counterbore for retaining said cup-shaped members and sealing ring in place, and a stop sleeve disposed in surrounding relation with the body of said plunger, said stop sleeve being constructed and arranged to accost said arcuate shoes on said plunger to define the outer extremity of plunger stroke and to permit the application to said sealing ring of a total compression thrust equal to that produced over an area equivalent to the total cross-sectional area of the bore in said cylinder.

THEO SHERWEN. 15
